EXPANSION ROOF STRUCTURE WITH
COUNTERBALANCING MEANSLester A. Wilkin, East Chicago, Ind., assignor to
Graver Tank & Mfg. Co., Inc., Catasauqua, Pa.,
a corporation of Delaware

Application December 4, 1941, Serial No. 421,580

2 Claims. (Cl. 48—176)

The invention relates to expansion roof tanks and has more particular reference to an expansion roof of the laundry type wherein guide posts depending from the roof are connected by flexible cables to provide stabilizing means for controlling vertical movements of the roof whereby the vapor space within the tank may be varied.

The present invention is an improvement over that shown in the Lester A. Wilkin and Charles L. Marner Patent No. 2,287,586 issued June 23, 1942, for Outside stabilizing means for expansion roof tanks. In that application it is explained that upward vertical movement of the roof to increase the vapor space within the tank is necessary to retain the volatile vapors produced during the heat of the day so that the vapors can be condensed by the cooler night temperature. These volatile fractions are thereby conserved and substantially the same procedure takes place upon filling of expansion roof storage tanks since the filling operation increases the production of vapors which are accommodated by the upward movement of the roof, thereby maintaining a substantially uniform pressure on the roof.

Unless counter-balancing means are employed the vapor pressure necessary to cause movement of the expansion roof in an upward direction is determined primarily by the weight of the roof including the weight of stabilizing means having fixed relation thereto and which move with the roof. However, by counter-balancing the dead weight of such a roof it is possible to secure operation at much lower pressures. Operation at these low pressures is desirable since the vapor space in an expansion roof tank is often connected with the vapor space of ordinary roof tanks built to safely withstand a very low maximum vapor pressure.

An object of the invention is to provide counter-balancing means for a movable roof of the gas holder type having outside stabilizing mechanism for connection therewith whereby the counter-balanced roof will be maintained substantially horizontal during vertical movement.

Another object is to provide improved counter-balancing means for an expansion roof which will be located exteriorly of the tank so as to be readily available for inspection and repair.

With these and various other objects in view, the invention may consist of certain novel features of construction and operation as will be more fully described and particularly pointed out in the specification, drawings and claims appended hereto.

In the drawings which illustrate an embodiment of the device and wherein like reference characters are used to designate like parts—

Figure 1 is an elevational view of an expansion tank having outside stabilizing mechanism for the movable roof constructed to accommodate the improved counter-balancing means of the invention;

Figure 2 is a fragmentary enlarged elevational view with the rain-shed skirt removed to clearly show the outside stabilizing mechanism and the improved counter-balancing means associated therewith;

Figure 3 is a fragmentary horizontal sectional view showing the location of the depending posts and sheaves circumferentially of the tank;

Figure 4 is a fragmentary vertical sectional view taken substantially along line 4—4 of Figure 2 showing a depending post and the mechanism associated therewith including sheaves and the connecting flexible cables; and

Figure 5 is a fragmentary vertical sectional view taken along line 5—5 of Figure 2 and more particularly showing the double sheave structure required for the counter-balancing weight.

In Figure 1 the invention is shown as applied to an expansion roof tank having cylindrical walls 10, a bottom 11, which may rest directly on the earth or other suitable support, and a movable roof 12. The cylindrical walls 10 and the bottom 11 provide an open top container which is closed by the movable roof 12 to retain gases or liquids within the structure. The cylindrical walls 10 at their upper ends are provided with a laundry 13 including a base or bottom member 14 supported and suitably reinforced at intervals by the angle brackets 15 extending inwardly from the side walls 10. The laundry at its upper end is likewise reinforced by angle members 16 which additionally provide supporting means whereby the rafters 17 are secured to the shell of the tank. The rafters have a slight inclination to provide a cone-shaped supporting surface for the movable roof 12 and said roof rests upon the rafters when in deflated position.

The movable roof in the form of a holder bell includes a circular portion 18 for covering the entire area of the open top tank structure. Depending from said circular portion adjacent the periphery thereof is a skirt 20 providing a dip ring with respect to the laundry 13 and which accordingly has location within said laundry. The roof is completed by a peripheral portion 21 welded to the circumference of the circular por-

tion 18 of the roof and which is substantially horizontal, as clearly shown in Figures 4 and 5. The inner end of the peripheral portion 21 has a depending strip 22 welded thereto which is backed up by the dip ring 20. The exterior edge is provided with a depending strip 23 and it will be understood that both said strips extend circumferentially around the roof. Strip 23 provides supporting means for the rain shed skirt 24 which is suitably welded to the exterior of the strip and depends vertically downward therefrom. The rain-shed skirt may be reinforced at intervals by angles 25 and the lower edge of said skirt is additionally strengthened by the angle 26 and the angle plates 27. The skirt 24 or weather hood is concentric with the depending dip ring 20, and the proper spaced relation is maintained with respect to the tank shell to accommodate the stabilizing means for the roof.

Depending from the roof in spaced relation circumferentially of the roof are a plurality of posts 28 which are located midway between the rain-shed skirt 24 and the cylindrical walls 10 of the tank. Each post is secured to the roof at its upper end through a box-like structure including depending side plates 29 and 30, Figure 2, which extend between strips 22 and 23, being suitably welded thereto, and which have approximately the same depth as the circumferential strips. Plates 29 and 30 support a bottom member 31 and a post 28 is suitably welded to said bottom plate. In this manner each post has securement to the roof and the roof structure is reinforced above each post by the rib 32 which extends substantially radially of the roof.

Each post extends through openings in girders projecting outwardly from the tank shell. The top girder 33 extends completely around the tank and is strengthened by the vertical member 34 which is suitably welded to the outer edge of said girder. The girder 33 supports brackets 35 journaled rollers 36 having rolling contact with their particular depending post 28. A lower individual girder is associated with each depending post identified by numeral 37 and brackets 38 are supported in a like manner by these individual girders, each journaled rollers 39 also for guiding contact with their particular depending post. Girder 37 is suitably strengthened and reinforced by depending side plates 40 and 41 which are joined by a front end plate 42. This box-like structure, including the girder 37, which can be considered as closing the top of the same, is welded to the shell of the tank and projects laterally from said shell in position to accommodate its particular depending post, as clearly shown in the drawings.

Flexible cables are provided for operatively connecting the depending posts with each other. More particularly the bottom of each post is connected by a chain with the top of an adjacent post in a direction toward the right, Figure 2. A plate 43 is welded at the bottom of each post and the same retains an eye bolt 44 to which the flexible chain 45 is secured. Accordingly, a chain 45 has connection with the bottom of each post and said chain extends upwardly, passing over a sheave 46 and then extends circumferentially of the tank shell until an adjacent post is reached, whereupon the chain passes under sheave 47 and then upwardly for connection with bottom plate 31 by means of the eye bolt 48. Sheave 46 is suitably journaled below girder 33 by the depending supports 50 which provide journaled means 51, Figure 4, for said sheave. The bottom of each

depending support 50 is joined by the base plate 52 suitably welded thereto and which is also welded to the tank shell. The sheave 47, Figure 5, is supported from girder 33 in a similar manner by depending supports 53 which likewise provide journaled means 54 for said sheave. The depending supports are secured to each other and to the tank shell by a base 55.

The structure for journaled sheave 47, which is positioned on the left hand side of each depending post, Figure 2, also journals a companion sheave 56 for the counter-balancing means to be presently described. Sheaves 46 and 47 are opposite each other since one is located on the right hand side of its respective depending post and the other on the left hand side of the post. Whereas, the flexible chain 45 passes over sheave 46 the said chain passes under sheave 47. Therefore during upward movement of the roof, sheave 46 will rotate clockwise and sheave 47 will rotate counter-clockwise. During downward movement of the roof the rotation of the respective sheaves is reversed.

It has been found desirable to counter-balance expansion roofs such as above described in order that the roof may operate on extremely low vapor pressures. In actual practice it is desirable that tanks equipped with expansion roofs operate on less than one ounce pressure per square inch. If such operation can be secured these expansion tanks can be used to store the vapors from a number of conventional fixed roof tanks. The present invention proposes to counter-balance the movable roof 12 by the provision of a plurality of counter-balancing weights 58, a weight being positioned in associated relation with each depending post. By means of the flexible chain 59 each counter-balancing weight is connected to the base of its respective depending post, the said chain passing over sheave 56 provided therefor and extending downwardly for connection to plate 43 which is effected by means of the eye bolt 60. The counter-balancing weights 58 are therefore located on the exterior of the tank shell along with the stabilizing means including the depending posts 28 and the flexible chains 45 which operatively connect adjacent posts. Therefore the entire structure can be readily inspected and repaired and although the same is on the outside of the tank it is substantially protected from the weather by the rain-shed skirt 24.

During operation of the movable roof the launder 13 will contain oil or water as a sealing medium for the dip ring 20 so that the interior of the tank is sealed from the atmosphere although the roof is free to move vertically to increase or decrease the vapor space within the tank. When the vapor pressure within is sufficient to cause upward movement of the roof, the movement is controlled by the depending posts and the cables which connect the same. Each post is suitably guided during said movement and as a result of the cables the entire roof is caused to move to the same extent and thus the roof during movement will maintain a substantially horizontal position. As previously explained, sheave 46 and sheave 47 for each depending post will rotate in opposite directions during upward and downward movement of the roof. However, sheave 47 and its companion sheave 56 for the counter-balancing means have rotation in unison and in the same direction. This takes place notwithstanding that the cable 45 passes under sheave 47, whereas, cable 59

passes over sheave 56. The action of each counter-balancing weight 58 is to urge the roof 12 upwardly, this said force being communicated to the roof through the depending posts since the cable from the counter-balancing weight has connection with the posts at the bottom end thereof. By proper adjustment of weights 58 the desired counter-balancing of the movable roof can be effected and the roof can be caused to move upwardly to increase the vapor space of the tank at very low maximum vapor pressures.

Each flexible cable 45 connecting certain adjacent posts will include an intermediate portion between the sheaves 46 and 47 extending circumferentially of the tank. In Figure 2 this circumferential direction is toward the right since each cable is fixed to the bottom of the depending post on the left and has securement at its other end to the top of the depending post on the right. As the distance between posts in large tanks may be considerable, it has been found necessary to provide an intermediate pulley 61 projecting outwardly from the tank shell and located below the circumferential girder 33. The pulley contacts the intermediate portion of its respective cable 45 and by so doing positions the central portion of the cable outwardly from the tank shell so that no rubbing between the cable and tank shell will take place.

The invention is not to be limited to or by details of construction of the particular embodiment thereof illustrated by the drawings, as various other forms of the device will of course be apparent to those skilled in the art without departing from the spirit of the invention or the scope of the claims.

What is claimed is:

1. In a tank having an expansion roof with sealing means between the roof and the tank shell, of a plurality of posts depending from the

5 roof in spaced relation circumferentially thereof and located externally of the tank, a girder disposed laterally outward from the tank shell and having openings through which the posts extend, a single sheave supported by the girder on one side of each post, a pair of sheaves supported by the girder on the other side of each post, cables connecting certain posts to maintain the roof substantially horizontal during its up and down movements, each cable passing over its respective single sheave and passing under one of a pair of sheaves, a flexible cable fixed to the end of each post and extending upward to pass over the other sheave of said pair and then depending downward therefrom, and a counter-balancing weight fixed to the depending end of the flexible cable.

10 2. In a tank having an expansion roof with sealing means between the roof and the tank shell, of a plurality of posts depending from the roof in spaced relation circumferentially thereof and located externally of the tank, a girder disposed laterally outward from the tank shell and having openings through which the posts extend, 15 a single sheave supported from the undersurface of the girder on one side of each post, a pair of sheaves having a common axis and being supported from the undersurface of the girder on the other side of each post, cables connecting certain adjacent posts to maintain the roof substantially horizontal during its up and down travel, each cable passing over its respective single sheave and passing under one of a pair of sheaves, another cable fixed to the end of each 20 post and extending upward to pass over the other sheave of said pair and then depending downward therefrom, and a counter-balancing weight attached to the depending end of the last mentioned cable.

40

LESTER A. WILKIN.
